UNITED STATES PATENT OFFICE.

GEORGE W. COMBS, OF LEAVENWORTH, KANSAS.

DRIVING AND RESTRAINING MEANS FOR SELF-BALANCING GYRATORY STRUCTURES.

1,123,171.

Specification of Letters Patent. Patented Dec. 29, 1914.

Application filed March 7, 1910. Serial No. 547,879.

To all whom it may concern:

Be it known that I, GEORGE W. COMBS, a citizen of the United States, residing at Leavenworth, in the county of Leavenworth and State of Kansas, have invented certain new and useful Improvements in Driving and Restraining Means for Self-Balancing Gyratory Structures, of which the following is a specification.

10 My invention relates to improvements in driving and restraining means for self-balancing gyratory structures, such as screens, flour-sifters, bolters, sorting-machines, etc., and my principal object is to provide new 15 and novel means for overcoming lunging or abnormal throw of the structure while in operation.

In order that the invention may be fully understood, reference will now be made to 20 the accompanying drawings, in which:

Figure 1 shows a side elevation partly in section of a gyratory structure provided with my improvements. Fig. 2 is a horizontal section taken on line II—II of Fig. 25 1. Fig. 3 is a vertical section on line III of Fig. 1. Fig. 4 is a horizontal section on line IV—IV of Fig. 3. Fig. 5 is a modified form of structure provided with my improved driving and restraining means. 30 Fig. 6 is a vertical section on line VI of Fig. 5, and Fig. 7 is a horizontal section on line VII—VII of Fig. 6.

1 designates a sifter structure, freely-suspended for gyration by flexible rods 2, 35 attached to a point overhead as a ceiling of the building containing the structure. Structure 1 is provided with centrally-disposed bearings 3 in which a shaft 4 for actuating the structure is journaled, said 40 shaft being provided with eccentric-weights 5 to assist in imparting a gyratory motion to the structure. Shaft 4 has axial movement in bearings 3, so that it will not move upwardly with the structure when the same 45 swings outward and upward into its gyratory path.

6 designates a collar fixed to the lower portion of the shaft by a set-screw 7 and preferably abutting against the lower bearing 3 to prevent the shaft from moving upward without tending to raise the structure therewith, as in the present instance I utilize not only the weight of the shaft and the eccentric-weights carried thereby, but 55 also the weight of the structure 1, in restraining the same from abnormal throw.

I, however, do not limit myself to this arrangement as collar 6 may be dispensed with in which instance shaft 4 will be free to move vertically independently of the 60 structure, and with the weights, assist materially in restraining the structure from abnormal throw.

8 designates an eccentric-pin secured to the lower end of shaft 4, and extending 65 downward into a lubricant-chamber 9, normally closed by a lid 10, loosely-mounted thereon, so that said lid may move laterally in any direction with pin 8, which it loosely embraces. Pin 8 is carried by a weighted 70 restraining member 11, comprising in its preferred form a circular weighted portion 12, extending in a horizontal plane, an upwardly-extending wall 13, forming a centrally-disposed lubricant-chamber 14, and a 75 central portion 15 secured to the main portion with set-screws 16, and provided with a central upwardly-extending stem 17, terminating in a spherical head 18, freely seated in a socket-member 19 fixed to the 80 lower end of pin 8 to protect said end from wear. The centrally-disposed portion 15 terminates at its lower end in a convex surface 20, which is free to rock in any direction upon the flat surface 21 of a retaining 85 member 22, whereby the restraining member 11 is carried. Member 22 is arranged in axial alinement with member 11 and has a convex periphery 23 fitting snugly within the concaved portion 24 of member 11, the 90 connection between the two being similar to that of a ball-and-socket joint, so that while member 11 is free to rock in any direction upon member 22, it is prevented by the latter from shifting laterally against 95 the interior of the lubricant-chamber. Member 22 is fixed upon a centrally-disposed step-bearing 25, extending upwardly within the lubricant-chamber to support the restraining member above the bottom of 100 said chamber, so that it will not contact therewith while in operation.

Lubricant-chamber 9 is surrounded by a flange 26 supported by a base-plate 27 provided with set-screws 28 to adjust the lubricant-chamber concentrically with the eccentric-pin 8.

29 designates a cushion interposed between flange 26 and base-plate 27, to allow the restraining member 11 to yield slightly 110 beneath the weight of the structure in overcoming abnormal gyration thereof, said

cushion being compressed by the downward pressure of member 11 when resisted by downward pressure of the structure 1.

Pin 8 is provided with a fixedly-mounted 5 driver 30 driven by a flexible member or endless belt 31, which also assists in restraining the structure from abnormal throw. Belt 31 runs over a pair of idlers 32 and around a stationary drive-pulley 33, 10 fixed upon a journaled shaft 34. Belt 31 is assisted in restraining the structure from abnormal throw by a flexible member or endless belt 35, adjustably-mounted upon a base-plate 38 provided with set-screws 39 15 whereby idler 36 may be adjusted backward or forward to tension belts 31 and 35. Base-plate 38 is also provided with set-screws 40 to adjust the bracket and the idler 36 laterally. Idlers 32 are carried by brackets 41 20 adjustably mounted upon base-plates 42, provided with set-screws 43 to adjust the brackets backward or forward for the purpose of tensioning belts 31 and 35. Base-plates 42 are also provided with set-screws 25 44 to adjust the brackets 41 laterally.

When structure 1 is in operation, any tendency to lunge or leave its true gyratory course and thus cause the eccentric-pin to move in an orbit, is resisted by the restraining member 11, which is caused to rock or swing upon the retaining member 22 by any lateral or orbital movement of said pin. This movement, owing to the long curve of the convex surface 20 of the restraining 30 member, tends to raise the same against the resistance of its weighted portion 12, the eccentric-pin 8, shaft 4, and weights 5, all of which, bearing downward thereon, tend to restore said restraining member to its normal position shown in Fig. 3, and thus return the structure to its true path of travel. Resistance to lunging of the structure is further increased if collar 6 be applied to shaft 4, as upward movement of said shaft 40 will then be further resisted by the added weight of said structure. Cushion 29, however, will yield under the weight of structure 1, so that the latter will be lifted only in rare instances, as I find in practice that the weight of the shaft and the parts carried thereby, together with the weighted member 11, is ordinarily sufficient to overcome abnormal throw of the structure. The belts 31 and 35 also coact with the restraining 50 means, just mentioned, in holding the structure to its true gyratory path and in overcoming abnormal throw thereof, as said belts pull in opposite directions on driver 30, and thus tend to overcome lateral movement thereof.

The construction and operation of the parts of the modified form shown in Figs. 5 to 7, inclusive, is substantially the same as that shown in the preferred form, but in order that said modified form may be fully

understood, reference in detail will now be made thereto: 1^a designates a sifter structure of the four-box type disclosed by U. S. Letters Patent No. 12,894 (reissue), freely supported for gyration by flexible rods 2^a, and connected in pairs by diagonally-arranged bridge-trees containing centrally-disposed bearings 3^a, in which a crank-shaft 4^a is journaled to actuate the structure. 6^a designates a pair of collars fixed to crank-shaft 4^a and engaging the undersides of two bearings located in two bridge-trees of the sifter 1^a, said collars being suitably fixed to the crank-shaft 4^a. The lower end of crank-shaft 4^a extends downward into a lubricant-chamber 9^a normally closed by a lid 10^a loosely-mounted thereon so that it can move laterally in any direction with the crank-shaft. The crank-shaft 4^a is carried by a weighted restraining member 11^a comprising a weighted portion 12^a, and a central portion 15^a terminating in a spherical head 18^a freely seated in a socket-member 19^a fixed to the lower end of the crank-shaft 4^a. The weighted portion 12^a terminates at its 90 lower end in a long convex surface 20^a, which is free to rock in any direction upon the flat surface 21^a of a steel button fixed upon a centrally-disposed step-bearing 25^a, formed by the lower portion of the lubricant-chamber 9^a. The reduced lower portion of the lubricant-chamber 9^a loosely embraces the convex periphery 23^a of the weighted portion 12^a of the restraining member and prevents the lower portion of the latter from moving laterally over the step-bearing, although, as above stated it is free to rock in any direction thereon, should the lower end of the crank-shaft move laterally or orbitally. While the restraining member 15^a is sufficient under ordinary circumstances to limit lateral or orbital movement of the crank-shaft, such movement is positively checked after attaining certain proportions by a roller 24^a loosely-embracing the lower portion of the crank-shaft and adapted to contact with the vertical interior face 24^b of the lubricant-chamber. Roller 24^a is supported independently of the crank-shaft by a horizontal face 24^c within the 115 lubricant-chamber 9^a. Lubricant-chamber 9^a is surrounded by a flange 26^a supported by a base-plate 27^a provided with set-screws 28^a to adjust the lubricant-chamber concentrically with the lower end of the crank-shaft. 29^a designates an annular cushion interposed between flange 26^a and base-plate 27^a to assist the restraining member 11^a in 120 overcoming abnormal gyration of the structure. 30^a designates a driver fixed to the lower portion of shaft 4^a and driven by an endless belt 31^a which assists member 11^a in restraining the structure from abnormal throw. Belt 31^a runs over idlers 32^a and around a stationary drive-pulley 33^a, fixed 130

upon a journaled shaft 34^a. Belt 31^a is assisted in restraining the structure from abnormal throw by an endless belt 35^a running around driver 30^a and an idler 36^a carried by a bracket 37^a, adjustably mounted upon a base-plate 38^a, provided with set-screws 39^a, whereby idler 36^a may be adjusted backward or forward to tension belts 31^a and 35^a. Base-plate 38^a is also provided with set-screws 40^a to adjust the bracket 37^a and the idler laterally. Idlers 32^a are carried by brackets 41^a adjustably mounted upon base-plates 42^a, provided with set-screws 43^a to adjust the brackets backward or forward to tension belts 31^a and 35^a. Base-plates 42^a are also provided with set-screws 44^a to adjust the brackets 41^a laterally thereon.

Having thus described my invention, what I claim is:

1. In combination, a freely supported structure, a shaft for actuating the same, and a rockingly-mounted restraining element carrying the weight of the shaft and coacting therewith to restrain the structure from abnormal throw, said element being normally in axial alinement with the shaft.

2. In combination, a body freely supported for gyration, a vertically-positioned shaft thereto for actuating the same, eccentric weights on said shaft, an eccentric-pin carrying the weight of the shaft and the weights carried thereby, and a rockingly-mounted weighted restraining member having a ball-and-socket connection with said eccentric-pin to restrain the same from lateral or orbital movement.

3. In combination, a normally-gyratable structure, a shaft thereto for actuating the same, means fixed to said shaft to prevent the same from moving upward independently of the structure, and restraining means carrying the weight of the shaft and tending to raise the same when the structure leaves its true gyratory path.

4. In combination, a structure freely supported for gyration, and restraining means operatively connected with said structure and tending to lift the same when it leaves its true gyratory path, said restraining means being yieldingly supported so that it may move downward beneath the weight of the structure when the same leaves normal path of gyration.

5. In combination, a gyrovatory body, restraining means coacting with said body to restrain the same from abnormal throw by tending to lift the weight thereof, and resilient means supporting said restraining means to allow the same limited movement beneath the weight of the body.

6. In combination, a gyrovatory body, a shaft thereto for actuating the same, means fixed to said shaft to prevent upward movement thereof independent of the body, re-

straining means tending to raise the shaft when the body leaves its true gyrovatory path, and a cushion to allow limited downward movement of said restraining means beneath the weight of said body.

70

7. In combination, a structure, means freely-supporting the same for gyration, a restraining member to prevent the structure from lunging while in operation, said restraining member including a weighted portion, and a retaining member having a convex periphery snugly embraced by the restraining member which is free to rock or swing in any direction.

75

8. In combination, a normally-gyratable structure, means to prevent the same from rotating, a weighted restraining member coacting with the structure to steady the same, said restraining member having a convex surface, and a retaining member for said restraining member having a flat surface movably engaged by the convex surface of the restraining member.

85

9. In combination, a gyrovatory structure, restraining means, to steady said structure, a lubricant-chamber in which said restraining means is mounted, and cushioning means to permit vertical movement of said chamber under varied pressure.

90

10. In combination, a structure freely supported for gyration, means for imparting a gyrovatory motion thereto, restraining means to steady the structure, and a yieldingly-mounted lubricant-chamber in which said restraining means is mounted.

100

11. In combination, a freely-supported structure, means for imparting a gyrovatory motion thereto, restraining means to steady said structure to prevent the latter from lunging, a lubricant-chamber in which said restraining means is operatively mounted, and resilient means supporting said chamber.

105

12. In combination, a gyrovatory structure, restraining means coacting with said structure to prevent the same from lunging, and a lubricant-chamber in which said restraining means is operatively mounted, said lubricant-chamber being yieldingly-mounted to coöperate with said restraining means.

115

13. In combination, a gyrovatory structure, a shaft thereto, restraining means coacting with said shaft to steady the structure, a lubricant-chamber containing said restraining means and into which the lower end of said shaft extends, and means for adjusting said lubricant-chamber concentrically with the shaft.

120

14. In combination a freely suspended structure, a shaft thereto, a pulley fixed to said shaft, endless driving and restraining means to drive the pulley and restrain the structure from abnormal throw, and restraining means tending to lift the structure to assist in steadyng the same.

125

130

15. In combination, a freely-suspended structure, a shaft thereto, for actuating the same, a pulley fixed to said shaft, yielding means for driving said pulley and restraining the structure from abnormal throw, and rockingly-mounted means coacting with the yielding driving and restraining means in steadyng the structure.
16. In combination, a freely-supported structure, a shaft thereto, a collar fixed to said shaft and abutting against an under portion of the structure, and restraining means supporting the weight of the shaft and tending to lift the same when the structure leaves its true gyratory course.
17. In combination, a gyratory structure including a shaft, and a rockingly-mounted restraining member for the structure including a spherical head upon which the shaft rests so that the same will not rock the said restraining member, and an upwardly-extending wall forming a lubricant-chamber containing the lower end of the shaft and said spherical head.
18. In combination, a gyratory structure, a shaft thereto, a driver for said shaft, and a restraining member tending to restrain the structure from lunging, said restraining member having a circular weighted portion and a centrally-upwardly extending stem having a ball-and-socket connection with the shaft.
19. In combination, a gyratory structure, a shaft thereto, a retaining member below the shaft and having a convex periphery, and a restraining member rockingly-mounted on said retaining member, said restraining member having a convex surface engaging the retaining member and a central upwardly-extending stem having a ball-and-socket connection with the shaft.

In testimony whereof I affix my signature, in the presence of two witnesses.

GEORGE W. COMBS.
